(57) **CLAIM**

The ornamental design for an insert for railing top rail, as shown and described.

DESCRIPTION

FIG. 1 is a perspective view of our insert for railing top rail; FIG. 2 is an end view thereof,

FIG. 3 is a left side view thereof, the right side being a mirror image thereof;

FIG. 4 is a top view thereof; and,

FIG. 5 is a bottom view thereof.

The break lines depict bounds of the claim. The portion between the break lines forms no part of the claimed design.
